(57) **CLAIM**

The ornamental design for a bottom-entry pet carrying backpack, as shown and described.

DESCRIPTION

FIG. 1 is a perspective view of a bottom-entry pet carrying backpack showing the new design.

FIG. 2 is a back view of the bottom-entry pet carrying backpack shown in FIG. 1.

FIG. 3 is a front view of the bottom-entry pet carrying backpack shown in FIG. 1.

FIG. 4 is a side view of the bottom-entry pet carrying backpack shown in FIG. 1.

FIG. 5 is a side view of the bottom-entry pet carrying backpack shown in FIG. 1.

FIG. 6 is a top view of the bottom-entry pet carrying backpack shown in FIG. 1; and,

FIG. 7 is a bottom view of the bottom-entry pet carrying backpack shown in FIG. 1.

The broken lines illustrate stitching and form part of the claimed design.

The dash-dot-dash broken lines illustrate portions of the bottom-entry pet carrying backpack that form no part of the claimed design.

1 Claim, 6 Drawing Sheets
